UNITED STATES PATENT OFFICE

2,360,386

HEAT EXCHANGER

George H. Young, Indianapolis, Ind., assignor to
B. F. Sturtevant Company, Boston, Mass.

Application March 28, 1942, Serial No. 436,567

4 Claims. (Cl. 257—137)

This invention relates to heat exchangers for varying the temperature of air and has as its object the accurate control of the effect of the heat exchangers whereby more uniform air temperatures may be maintained.

The usual method of controlling the effect of heat exchangers such, for example, as unit heaters, is to damper the air from the heater for decreasing the heated air volume when less heat is required, and for increasing the heated air volume when more heat is required. A disadvantage of this method is that the volume of air recirculated is not uniform.

This invention provides for varying the volume of heated air from a unit without varying the total volume of air which is delivered by the unit.

In a preferred embodiment of the invention a two inlet fan has one inlet connected to draw air through a heater, and the other inlet arranged to draw in unheated air. The outlet of the fan discharges into the space to be heated. Spin inducing vanes are placed in each inlet. When less heat is required, the vanes in the inlet connected to the heater are adjusted towards closed position while the vanes in the other inlet are conformably adjusted towards open position. The fan thus while delivering a constant volume of air, delivers smaller volumes of heated air when less heat is required, and delivers greater volumes of heated air when more heat is required.

The invention will now be described with reference to the drawing, of which:

Fig. 1 is a side elevation of an air heating unit embodying this invention, and

Fig. 2 is a sectional view taken along the lines 2—2 of Fig. 1.

The unit 5 has a plurality of parallel vertical rows of circular finned tubes 6. The tubes are connected as shown in Fig. 2 to an upper header 7 and to a lower header 8 for the supply of a heating fluid which, for example, may be steam.

The unit 5 is supported at its opposite ends by the transformation plates 9 from the centrifugal fans 10. The plates 9 also form converging outlets from the unit 5, connecting the inner inlets 11 of the fans with the interior of the unit.

The centrifugal fans 10 illustrated are similar to that disclosed in the Hagen Patent No. 1,939,413 except that the bearings 12 thereof are supported similar to the fan bearings disclosed in the Bartlett and Leonard Patent No. 2,113,391.

The fans 10 also have the outer inlets 13 which are open to the atmosphere and which serve to

supply unheated air into the fans as will be described.

The inlets 11 of the fans contain the spin vanes 14 which are rotated through the up and down movement of the arms 15 and 16 which cause rotation of gears in the gear assemblies indicated generally by 17 as disclosed in detail in said Hagen patent. The inlets 13 of the fans contain similar spin vanes 14 which are rotated through the up and down movement of the arms 15 and 18 which cause rotation of gears in the gear assemblies 17 associated with the vanes 14 in the inlets 13.

The arms 16 which serve to adjust the vanes 14 in the inlets 11 and the arms 18 which serve to adjust the vanes 14 in the inlets 13, are secured to the rock shaft 19 which in turn is arranged to be rotated through an angle of 180° by the piston 20 connected to the plunger armature 21 of the solenoid 22.

The winding of the solenoid 22 is connected in series with the thermostat 23 and a suitable electric source.

The arms 18 are placed 90° apart on the shaft 19 with respect to the arms 16 so that as illustrated by Fig. 1 the arms 18 are almost in their lowermost position with the vanes 14 associated therewith almost fully open, while the arms 16 are almost in their uppermost position with the vanes 14 associated therewith almost fully closed.

The action of the spin vanes 14 is disclosed fully in the Hagen Patent No. 1,846,863 and it is believed to be sufficient to state here that as the vanes are rotated towards their closed position, the air volume through the fan inlet in which they are placed, decreases conformably with the rotation of the vanes, and when they are rotated towards their open position, the air volume through them increases conformably with their rotation.

In operation, when the thermostat 23 calls for heat it energizes the solenoid 22 and causes it to rotate the shaft 19 and the arms 16 and 18 and through them to adjust the vanes 13 in the inlets 13 towards closed position, and the vanes 14 in the inlets 11 towards open position. This causes less unheated air to be drawn in through the inlets 13 and more air to be drawn in through the inlets 11 connected to the heater 5. Conversely when the thermostat 23 calls for less heat, the spring biased solenoid 22 rotates the shaft 19 in the other direction causing the arms 16 and 18 to adjust the vanes so that more unheated air is drawn in through the inlets 13, and less heated air through the inlets 11.

The dampers which previously have been used for controlling air volumes, in addition to varying the volume of delivered air, have caused power losses due to the air resistance they introduce.

The spin vanes utilized in this invention not only enable a constant air volume to be delivered but they offer substantially no resistance to the air and causing therefore practically no power losses. A constant speed motor may be used for driving the fan at constant speed for delivering unchanged air volumes throughout the range of adjustments.

The thermostat 23 and solenoid 22 may be of the graduated type affecting graduated adjustment of the spin vanes, or they may be of the on-off type for completely closing the vanes in one pair of inlets while completely opening the vanes in the other pair of inlets.

The thermostat 23 and the solenoid 22 may be omitted and manual adjustment of the vanes provided by means of the crank 24 at one end of the shaft 19.

While fans have been illustrated as being placed at opposite ends of the unit 5 for drawing air therethrough in both directions, one fan may be omitted and the end of the unit 5 to which it is shown connected may be closed.

While one embodiment of the invention has been described for the purpose of illustration, it should be understood that the invention is not limited to the exact apparatus and arrangement of apparatus illustrated as modifications thereof may be suggested by those skilled in the art without departure from the essence of the invention.

What is claimed is:

1. A heat exchanger for supplying tempered air to a space, comprising a heat exchange surface, a constant speed fan having two inlets and an outlet, means connecting one of said inlets with said surface and providing a passage for air drawn through said surface and said one inlet into said fan, the other of said inlets connecting with said space, and means including spin vanes in said inlets for increasing the volume of air through one

of said inlets and for simultaneously decreasing the volume of air through the other of said inlets, for varying the temperature of the air from said outlet.

5. 2. A heat exchanger for supplying tempered air to a space, comprising a centrifugal fan having opposed axial inlets and an outlet, an annular heat exchange surface in axial alignment with and connected to one of said inlets, the other of 10 said inlets connecting with said space, and means including spin vanes in said inlets for increasing the volume of air through one of said inlets and for simultaneously decreasing the volume of air through the other of said inlets, for varying the temperature of the air from said outlet.

3. A heat exchanger for supplying tempered air to a space, comprising an annular heat exchange surface, a pair of centrifugal fans having opposed axial inlets and an outlet, said fans being 20 arranged in axial alignment with said cylinder, one at each end thereof and each having its inner inlet connected to the adjacent end of said surface, for drawing air through said surface into said fans, the outer of said inlets connecting with said space, and means for increasing the 25 volume of air through said inner inlets and for simultaneously decreasing the volume of air through said outer inlets.

4. A heat exchanger for supplying tempered 30 air to a space, comprising an annular heat exchange surface, a pair of centrifugal fans having opposed axial inlets and an outlet, said fans being arranged in axial alignment with said cylinder, one at each end thereof and each having its 35 inner inlet connected to the adjacent end of said surface, for drawing air through said surface into said fans, the outer of said inlets connecting with said space, and means including spin vanes in said inlets for increasing the volume of air 40 through said inner inlets and for simultaneously decreasing the volume of air through said outer inlets.
